INVENTOR
James W. Thompson

BY *E. M. Marshall*
ATTORNEY

UNITED STATES PATENT OFFICE.

JAMES W. THOMPSON, OF WHITE PLAINS, NEW YORK.

INCINERATOR.

Application filed July 9, 1923. Serial No. 650,331.

To all whom it may concern:

Be it known that I, JAMES W. THOMPSON, a citizen of the United States, and a resident of White Plains, county of Westchester, 5 and State of New York, have invented certain new and useful Improvements in Incinerators, of which the following is a specification.

This invention relates to receptacles for 10 holding paper or other refuse or waste material while the refuse is being burned.

The salient object of the invention is to provide a receptacle of the character described that is simple but rugged in construction and can be economically manufactured.

Further objects of the invention will appear from the following specification taken 20 in connection with the drawings, which form a part of this application, and in which

Fig. 1 is a vertical sectional elevation illustrating a receptacle construction in accordance with the invention, and

Fig. 2 is a perspective view broadly broken away and showing the details of the construction illustrated in Fig. 1.

In the particular form of the invention shown, the receptacle comprises an elongated tubular woven wire member 10 having a plurality of reinforcing hoops 11, 12 and 13 secured thereto.

The hoops 11 and 12 are secured within the tubular member 10 by separate wire loops 14. The hoop 11 is secured adjacent the upper end of the tubular member and the hoop 12 is positioned intermediate the ends of the member 10.

The hoop 13 has secured thereto a plurality of cross strands of wire 15 which form the bottom of the receptacle and support the refuse in position to be burned. This hoop 13 is secured to the receptacle 10 by separate wire loops 16. The lower ends 17 of the wires forming the tubular member are bent upwardly to form rests for supporting the tubular member.

A cover 20 is hinged at 21 to the upper end of the tubular member and a hook 22 50 is carried by the cover and is adapted to en-

gage the hoop 11. The cover 20 comprises a hoop 23 and interlaced wires 24 secured to the hoop.

From the foregoing description, it will be seen that a simple, rugged and practical 55 construction of refuse container or receptacle has been designed and it will be obvious that this receptacle can be economically manufactured.

Although one specific embodiment of the 60 invention has been particularly shown and described, it will be understood that the invention is capable of modification and that changes in the construction and in the arrangement of the various cooperating parts 65 may be made without departing from the spirit or scope of the invention, as expressed in the following claims.

What I claim is:

1. A receptacle for burning refuse, comprising a tubular woven wire body, reinforcing hoops secured to the woven wire body intermediate of its ends and adjacent the upper and lower ends thereof, the lower ends of the wires of the tubular body below 70 the hoop being interlocked to form a plurality of supports for the receptacle, woven wire secured to the hoop adjacent the lower end of the receptacle and forming a bottom for said receptacle, and a woven wire cover 75 for the receptacle.

2. A receptacle for burning refuse, comprising a tubular woven wire body, reinforcing hoops secured to the inner face of said body intermediate of its ends and adjacent its upper and lower ends, the lower ends of the wires below the hoop being interlocked to form a plurality of supports for the receptacle, woven wire secured to the hoop adjacent the lower end forming a 80 bottom for the receptacle, and a cover for the receptacle formed of a hoop and woven wire secured thereto, sundry of the upper ends of wires of the body being looped around the hoop of the cover to hinge the 85 cover thereto.

In witness whereof, I have hereunto set my hand this 2 day of July, 1923.

JAMES W. THOMPSON.
